DECORTICATING MACHINE

William A. Boyce, Bridgeport, Conn., assignor to
Anton F. Burkhardt, New York, N. Y.

Application April 13, 1940, Serial No. 329,513

3 Claims. (Cl. 19—30)

My present invention relates to fiber preparing devices, and more particularly to an improved scutching machine for flax, hemp, ramie, and the like.

In carrying out my invention I provide in a scutching machine having the usual stalk feeding and preparing mechanism for feeding stalks to and over an anvil, and into operative association with a scutching rotor or rotors, or a train of rotors, for mechanically removing the shives from the fibrous part of the stalks. In my improved device I have devised a new and improved form of apron over which the stalks of fiber are fed from the anvil and with which the scutching rotor or rotors is or are in direct association.

In the present form of my invention, I provide means for reciprocating the apron so as to have relative movement with respect to the scutching rotor or rotors and independently of the rotary movement of such rotor or rotors. The apron may have its working face lying in a plane or in a curved surface which preferably, for mechanical reasons, may lie in a surface of which the center of rotation of the rotor or rotors is the center. Further, the working surface of the apron may be plain or corrugated, and in some instances it may be desirable to provide the body of the apron lying between the projections which form the corrugations with perforations or openings to facilitate the disposal of the shives which are removed from the stalks of fibrous material.

A feature of my invention, therefore, is an improved scutching machine in which the apron associated with the scutching rotor or rotors is adapted to have a relative movement with respect to and independent of the rotary movement of the rotor.

Another feature of my invention is an improved scutching machine in which an apron is provided with an arcuate working face lying in a surface of revolution of approximately the same diameter as the diameter of the scutching rotor.

A still further feature of my invention is an improved scutching machine in which the apron associated with the scutching rotors has an oscillatory movement with respect to the center of rotation of the scutching rotor.

A still further feature of my invention is an improved scutching machine provided with a scutching rotor having associated therewith an apron, having a corrugated arcuate face, and in which there is provided a plurality of perforations extending through the body of the apron, and which perforations communicate with the

depressions between projections forming adjacent corrugations.

In the accompanying drawings:

Fig. 1 is a sectional elevation of a portion of a scutching machine in which one form of my invention is embodied.

Fig. 2 is a front elevation of the structure illustrated in Fig. 1.

Fig. 3 is a sectional elevation of a scutching machine similar to Fig. 1 and illustrating another form of my present invention, and

Fig. 4 is a front elevation of the apron illustrated in Fig. 3.

Referring to the drawings, 10 designates one of the side frame members, it being understood, naturally, that there are two side frame members and on top of such frame member is secured a table or platform 11. Secured to the end of the table or platform 11 is a plate 12, ordinarily of metal, the end 13 of which constitutes an anvil over which stalks 14 of fibrous material, such as flax, hemp, ramie, or the like, may be fed by any suitable crushing and feeding means and which crushing and feeding means prepares the stalks 14 of fibrous material for the scutching operation. Immediately above the plate 12 and adjacent the anvil 13 is a hold-down roller 15, the function of which is to hold down the stalks 14 of fiber and to facilitate the movement thereof into position to be engaged by the scutching rotor.

Adjacent to the anvil 13 is arranged a shaft 16 on which is mounted a scutching rotor 17 provided with a plurality of spaced radially extending scutching blades 18. The position of the shaft 16 and the diameter of the scutching rotor 17 and its blades 18 is so proportioned that, as the scutching rotor rotates in the direction of the arrow shown, the edges of the scutching blades 18 will come into association with the stalks 14, as the same move over the anvil 13 and will break the shives at the portions prepared by the feeding and crushing rolls (not shown, but above referred to).

Below the shaft 16 and parallel thereto is arranged a shaft 19 on which is mounted the scutching rotor 20 provided with a plurality of spaced radially extending scutching blades 21. The scutching rotor 20 with its scutching blades 21 is similar in construction and size to the scutching rotor 17 with its blades 18, and means (not shown) is provided for rotating the scutching rotors in the direction of the arrow shown and at the same speed as the speed of the scutching rotor 17, so that the scutching blades

of one rotor will intermesh with the scutching blades of the other rotor.

Associated with the scutching rotor 17 is an apron 22. As shown, at the ends of the scutching rotor are side plates 23, between which extend the apron 22, and the side plates 23 are, for convenience, rotatably mounted on the shaft 16. On the side frame members 10 are secured bearing blocks 24 in which is rotatably mounted a shaft 25. On the shaft 25 are secured eccentrics 26 which rotate in the eccentric straps 27 formed at the lower end of the connecting rods 28. Formed integral with the apron 22 adjacent the side plates 23 are lugs or ears 29. In each of the lugs or ears 29 is a stub shaft 30 and on which shafts are pivotally mounted the upper ends of the connecting rods 28. Suitable means is provided for rotating the shaft 25, and, therefore, it will be apparent that an oscillatory motion is imparted to the apron 22, and such motion is independent of the rotary motion imparted the scutching rotor 17 by the shaft 16.

As shown in Fig. 1, the working face of the apron 22 is corrugated, such corrugation being indicated by the reference numeral 31, and also it will be noted that such working face of the apron 22 lies in a surface of revolution which has a center substantially that of the shaft 16, although any form of surface may be employed. For example, the working surface of the apron 22 may lie in a plane which is ordinarily substantially perpendicular to a radius extending from the center of the shaft 16.

Referring now to Figs. 3 and 4, there is shown a variant of my invention from that illustrated in Figs. 1 and 2, and in which the apron 32, corresponding to the apron 22, is corrugated, the projections of the corrugations being indicated by the reference numeral 33 and with the space between adjacent projections 33 provided with a plurality of elongated perforations or slots 35. In this form, also, the working face of the apron 32 lies in a surface of revolution of which the center is substantially the center of the shaft 16, or may have any of the features of construction above described with respect to Fig. 1. It has been found, however, that the elongated perforations 35 effectively assist in disposing of the shives 36 which are broken from the stalks 14 of fibrous material by the scutching blades 18 of the scutching rotor 17. Where the elongated slots or perforations 35 are not employed it is found that the shives 36 will work into the depressions between adjacent corrugations 31 or 33 and will gradually work out therefrom. Such movement, however, is assisted materially by the presence of the elongated slots or perforations 35 and I consider the presence of such perforations an added and important feature of my invention.

In illustrating the present invention, no attempt has been made to show, either a driving member, or the interconnecting means for driving the rotors 17 and 20, nor the holdown roller 15, or the shaft 25. Such mechanical means as may be employed, are the usual mechanical means and an illustration or description thereof is not deemed necessary for a full and complete understanding of my invention.

The aprons 22 and 32 in their reciprocating

movement act on the stalks 14 of fibrous material as a scrubbing or wash board. In association with the edges of the blades on the scutching rotor 17 the corrugations or parallelly arranged projections on the working face of the aprons and because of the reciprocating movement imparted thereto insure that a scutching action is performed on what may be termed both sides of the stalks 14 of fibrous material as such stalks will be in a flattened condition. This action of the aprons, in association with the scutching rotor, facilitates removal of shives from the stalks 14 of fibrous material in a very marked manner.

Whereas I have described my invention by reference to specific forms thereof, it will be understood that many changes and modifications may be made without departing from the spirit of the invention.

I claim:

1. An apparatus for treating fibrous material comprising in combination an anvil over which stalks of fibrous material are fed, an apron located below said anvil and over which the stalks of fibrous material pass from the anvil, a scutching rotor provided with blades cooperating with the anvil and with the working face of the apron to remove shives from the fibrous material, and means for imparting an oscillatory movement to the apron in a path tangential to the surface of revolution generated by the scutching rotor in its rotary movement.

2. In an apparatus for treating fibrous material comprising in combination an anvil, a rotarily mounted scutching rotor provided with a plurality of spaced radially extending blades about the periphery thereof, an apron having an arcuate working face lying substantially in the surface of rotation of the edges of the scutching rotor blades, the working face of the apron having thereon a plurality of parallelly arranged spaced projections defining depressions in the material of the apron between adjacent projections, a plurality of perforations extending through the material of the apron and communicating with the aforesaid depressions, and means for imparting relative movement to the apron about the center of rotation of the scutching rotor and independently of the rotary movement of the scutching rotor.

3. In an apparatus for treating fibrous material comprising in combination an anvil, a rotarily mounted scutching rotor provided with a plurality of spaced radially extending blades about the periphery thereof, an apron having an arcuate working face lying substantially in the surface of rotation of the edges of the scutching rotor blades, the working face of the apron having thereon a plurality of parallelly arranged spaced projections defining depressions in the material of the apron between adjacent projections, a plurality of perforations extending through the material of the apron and communicating with the aforesaid depressions, and means for imparting a reciprocatory motion to the apron about the center of rotation of the scutching rotor and independently of the rotary movement of the scutching rotor.

WILLIAM A. BOYCE.
